(57) **CLAIM**

The ornamental design for a seat, as shown and described.

DESCRIPTION

FIG. 1 is a perspective view of the seat showing the new design in a first embodiment.

FIG. 2 is a top view thereof.

FIG. 3 is a front elevation view thereof.

FIG. 4 is a perspective view of the seat showing the new design in an alternative embodiment.

FIG. 5 is a top view thereof; and,

FIG. 6 is a front elevation view thereof.

The broken lines shown in the drawings are understood to represent stitching.
